Primary Examiner — Rosemary K Tarcza(74) *Attorney, Agent, or Firm* — NSIP Law(57) **CLAIM**

We claim the ornamental design for a wireless charging pad, as shown and described.

DESCRIPTION

FIG. 1 is a front perspective view of a wireless charging pad showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is another front perspective view, in which a cable in broken lines is provided to illustrate an example environment.

The broken lines in the figures showing portions of the wireless charging pad form no part of the claimed design. The broken line showing of the cable in FIG. 8 is for the purpose of illustrating environmental structure and forms no part of the claimed design.

The pair of closely spaced dot-dash broken lines in FIG. 8 indicates no particular length and forms no part of the claimed design.
